(57) **CLAIM**

The ornamental design for a handset, as shown and described.

DESCRIPTION

This Design Application is related to co-pending design application Ser. No. 29/363,179, filed Jun. 5, 2010, entitled "Handset". The disclosure of these design applications are considered part of and are incorporated by reference.

FIG. 1 is a front perspective view of a handset showing our new design;

FIG. 2 is a front view thereof;

FIG. 3 is a back view thereof;

FIG. 4 is a side view thereof;

FIG. 5 is another side view thereof;

FIG. 6 is a top view thereof; and,

FIG. 7 is a bottom view thereof.

The broken lines immediately adjacent the claimed surfaces represent boundaries of the claimed design. All other broken lines are directed to environment. The broken lines and unshaded regions bounded by broken lines form no part of the claimed design.
